UNITED STATES PATENT OFFICE.

HANS O. SWOBODA AND EARL M. RICHARDS, OF PITTSBURGH, PENNSYLVANIA, ASSIGNORS TO H. O. SWOBODA, INC., OF PITTSBURGH, PENNSYLVANIA, A CORPORATION OF PENNSYLVANIA.

CRACKING LIQUID HYDROCARBONS.

Application filed July 6, 1922. Serial No. 573,080.

Figure 1 is a diagrammatic sectional side elevation showing one form of apparatus for carrying out our invention; and

5 Figures 2 to 4 are diagrammatic views showing other forms of our apparatus.

Our invention relates to the cracking of hydrocarbons into hydrocarbons having a lower boiling point, and is designed to provide a new and improved apparatus and 10 method therefor.

In a long series of experiments, we have found that in a cracking system where oil is continuously fed through a pipe or conduit and vaporized and cracked through its 15 passage, the percentage of lower boiling point product produced in the higher percentages of yield depends quite largely on the temperature, particularly that in the hottest portion of the tube or conduit. Small 20 variations in temperature in the cracking zone proper, as well as in the conduit leading to the cracking zone, are found to produce large variations in yield.

In carrying out our invention, we preferably utilize the metallic tube or conduit itself as an electric resistance and by supplying electric heat to a zone portion or portions of the tube, we are enabled to regulate the temperature thereof accurately and 30 force in heat quickly after cracking begins, and thus obtain large yields.

Our invention also relates to recovering a portion of the heat of the cracked vapors and returning this heat to the heating zones 35 of the conduit, thus greatly reducing the amount of heat energy supplied and greatly improving the economy of the system. It also relates to a system of automatic temperature regulation hereinafter described.

40 We have also found that by dropping the oil to be cracked into a steam current passing through the cracking tube or conduit and insuring a considerable velocity of the steam, the carbon which is freed in cracking up. So far as we can determine, the steam 45 will be swept through and out of the cracking conduit, thus avoiding its being clogged up. In so far as we can determine, the steam performs the mechanical function of sweeping out this freed carbon when the steam is 50 maintained under sufficient velocity.

In Figure 1 of the drawings, we show one form of apparatus for carrying out our invention. In this form, 2 is the receptacle for untreated oil which is pumped into the

oil-preheating pipe 4 by a pump 3 provided 55 with a governor. The pump is shown as driven by a motor 6 and the amount of oil pumped is indicated by a flow meter 7, connected to the pipe leading to the pump. A pressure gage 5 is preferably connected to the 60 oil-preheating pipe 4 to indicate the pressure of oil in the preheater. 8 is a thermocouple arranged to measure the temperature of the untreated oil leaving the oil preheater, and 9 is an automatically controlled valve which 65 regulates the flow of the heat transfer medium to the jacket space around the oil preheater 4 to maintain constant the temperature indicated by the thermocouple 8. The valve 9 is operated by motor 10, which is 70 electrically connected to the control board 11 to which the thermocouple 8 is also connected to give automatic control. Such an automatic valve control system is available 75 in the open market. From the oil preheater 4, the preheated oil flows through pipe or duct 12 into the converter pipe 26, entering this pipe beyond the point where steam is introduced into the converter through a 80 duct 13.

14 is a water tank containing the water which is to be passed into the converter to mix with the oil, the water from reservoir 14 being pumped by a pump 15 into boiler 16. The pump 15 is driven by motor 17, and 85 18 is a pressure gage on the boiler to show the pressure of the steam in the boiler. 19 is an automatically controlled motor-operated valve controlling the flow of gas from a gas tank 20 through pipe 21 to the heater 22 of the boiler, the valve being actuated by motor 23, automatically controlled from the switch board 11 and actuated from the pressure gage 18 which is especially provided 90 with electrical contacts. The water passing from the pump to the boiler is passed through a water preheater 24, in which there is circulated around the feed pipe a portion of the heat transfer medium flowing from the converter through pipe 25 to the pipe 100 59 and pump 60.

The converter has an inner tube 26, to convey the oil and water introduced from the oil preheater and the boiler 16, and this converter tube leads to a catalyzer tube 27. 105 Jacket tubes 28 and 29 surround the converter tube 26 to convey the heat transfer medium which passes from the upper end

of the jacket space within pipe 28 through a bypass or deflecting device 31, which leads the heat transfer medium to the lower part of the jacket tube 29. This deflecting or bypass device is heated by a differential temperature and starting heater 33 and contains a check valve 32, to prevent the back flow of the heat transfer medium after once entering the bypass 31. The jacket spaces 10 are separated by the partition or deflector device 30. 34 is an automatically controlled motor-operated valve driven by motor 35, which is electrically connected to the control board 11 and actuated by thermocouple 36, located in the adjacent portion of the tube 26 below the baffle or partition separating the jacket spaces.

The catalyzer or cracking tube 27, which may be provided with any of the ordinary 20 catalytic material, such as molybdenum, vanadium, etc., or may be without any such material, is provided with electrical taps 38 and 39, connected to transformer 40, with tap-off changer 41, through which electrical 25 energy is supplied to the catalyzer tube. This portion of the conduit is preferably electrically insulated from the jacket tubes of the converter and condenser by insulating joints 42 and 43. The entire cracking conduit, including the oil preheater, converter, 30 catalyzer or cracking tube and condenser, is preferably formed of one continuous pipe or tube which is mechanically and electrically continuous. A thermocouple 44, 35 located in the catalyzer tube, in cooperation with other instrumentalities regulates the temperature of the vapors passing therethrough. A sample pipe 45 of small diameter also connects the catalyzer tube to sample equipment 46, which may contain a 40 coil of pipe in a tank containing a cooling medium with a tap-off, as shown.

The condenser comprises a tube 50, forming a continuation of the catalyzer tube, and 45 is surrounded by a jacket tube 51, the heat transfer medium being carried in the jacket space thus formed. The tube 50 has a tar trap 86, located in its intermediate portion to receive tar and similarly condensed heavy 50 hydrocarbons, and the jacket space around tube 50 has an outlet tube 52, connected to the jacket space of tube 28 of the converter through pipe 58. 53 is a differential temperature and heating burner receiving gas 55 through pipe 54, from gas tank 20, the gas supply being automatically controlled by motor-operated valve 55, actuated by thermocouple 56 in the converter tube just short of the catalyzer tube. A motor 57 operates valve 55. The heat transfer medium delivered through pipe 58 to the jacket space around the converter tube is withdrawn 60 from the jacket around the oil preheater through tube 59 by a pump 60, driven by a motor 61. This pump is provided with

a pressure gage 62, and with a safety valve 63. A reserve supply of distilled water is contained in reservoir 64 where steam is used as the heat transfer medium. The water passes from this reservoir to the heater 52 70 through a reducing valve system 65.

The receiving receptacle consists of a tank 66 to receive the condensed liquids, and the gas tank 20 to receive the gas, these products passing through pipe 67. A pipe 68 75 with valve 69 is shown as arranged to feed gas into the gas tank from other sources of gas supply, if needed.

From the tank 66 the treated oil may pass through pipe 71 to evaporator 70 having 80 a heater 72 supplied by gas drawn from gas tank 20 through pipe 73. This pipe may have the automatically controlled motor-operated valve 74, driven by motor 75, controlled from the control board 11 and actuated by thermocouple 76 inserted in the upper part of the evaporator 70. From the evaporator, the vapors pass through pipe 78 to a condensing tank 77.

On the control board are preferably 90 mounted meters 79 to indicate the volts, amperes and watts used by the electric heater, also instrument switches 80 and oil breaker 81 to connect and disconnect the transformer 40 from the electric service lines. 95 On this board are also preferably mounted pyrometers 82, to indicate the temperatures measured by the various thermocouples, relays 83, actuated by contacts on the pyrometers 82, and controlling the circuits of the 100 motors actuating the valves, and also switches 84, to control the various electrical circuits and a watthour meter 85 to record the energy consumption.

The apparatus, as a whole, may be and 105 preferably is encased in heat-insulating material as shown.

In starting the operation, the valve 69 is opened to admit gas from an external source to the gas tank and its interconnected pipes. The proper switch of group 84 on the control board is then thrown in to start motor 110 17, which thereupon drives the pump 15 to deliver water from the water tank into the boiler. The valve 19 is then opened and the burner 22 lighted and another switch of group 84 on the board is thrown in to start motor 23 into operation. Steam is thus developed, the pressure of which is shown 115 on the pressure gage 18. When a predetermined pressure is developed by this steam, the gage hand operates a contact mechanism which, in turn, operates a relay of group 83, on the switch board which causes the motor 120 23 to reduce the supply of gas through the valve 19, thus producing a drop in pressure. When the pressure drops a small amount, the gage hand operates another contact, causing the motor 23 to admit an increased 125 flow of gas. In this way, by means of these 130

contacts on the pressure gage and motor, the valve 19 will vary the gas flow and automatically maintain the steam pressure in the boiler 16 substantially constant.

5 Distilled water is then admitted to the differential temperature and starting heater 52 and the valve 55 is opened to permit flow of gas from the gas tank to the burner 53 which is lighted. At the same time, a 10 switch of group 84 is thrown in on the control board to start motor 57 into operation. By means of a relay of group 83 on the control board and the corresponding pyrometer of group 82, the motor will cause the valve 15 55 to vary the gas flow according to the temperature registration of the thermocouple 56. The heat transfer medium being converted into steam flows up through the tube 58, into the jacket space of the converter, thence through the check valve 32 and the differential temperature and starting heater 31. At this time, a switch of 20 group 84 is operated on the board to start the gas heater 33. The gas to this heater is 25 automatically regulated from thermocouple 36 by valve 34. The other motors are correspondingly controlled by pyrometers, relays and switches. The steam passing through the heater 31 conveys additional 30 heat to the converter and burners 53 and 33 function as starting heaters to supply heat to the heat transfer medium until such time as this medium will receive most of its heat from the operation of the apparatus. The 35 jacket steam flows to the upper end of the converter and thence passes down the restricted pipe 25 and also up through valve 9 into the jacket space of the oil preheater. Another switch should then be thrown in 40 to control valve 9 through its motor, pyrometer, relay and switch so that the heat transfer medium flowing through valve 9 will maintain a predetermined temperature at the thermocouple 8. From the jacket 45 space of the oil preheater, the heat transfer medium flows into pipe 59 and at this point the steam acting as a heat transfer medium has been condensed into water, and in this 50 form is delivered by pump 60 to the tube 51 of the condenser, whence it passes to the heater 52 and the cycle is then repeated.

Water is fed into the jackets and steam is circulated until the various thermocouples cause their pyrometers to regulate the temperatures desired for normal operation. A switch is then thrown in on the control board which starts motor 6 into operation, causing pump 3 to deliver oil from the reservoir to the oil preheater. This oil then 60 passes under pressure through the oil preheater where it is heated to a predetermined temperature, as regulated by valve 9 through the action of thermocouple 8. This preheated oil flows through duct 12 into the converter tube 26, where it drops into the

steam from boiler 16, the current of which, under the desired velocity, will carry out the carbon formed. The temperature of the oil and steam is preferably about 350 to 450°F. The mixture of steam and oil vapor 70 is then progressively heated as it passes through the converter tube 26 by the heated steam flowing in the counter direction in the jacket. The rate of progressive heating or raising of the temperature, however, is reduced after the mixture of oil and steam enters the lower portion of the converter tube surrounded by the jacket tube 28; since a lower rate of heat increase in this portion of the converter has here been found 80 by experiment to produce the most satisfactory results in cracking. Hence, more heat per unit area should be delivered into the portion of the converter tube surrounded by jacket tube 29, as compared with that 85 surrounded by jacket tube 28. This is effected by the differential temperature and starting heater 31 and the quantity of heat thus added is automatically controlled by the thermocouple 36, valve 34, motor 35, pyrometer on the control board, and relay on the control board.

After passing through the converter tube, the mixture of oil vapor and steam enters the catalyzer tube where it rapidly increases 95 in temperature through the heat energy forced into this tube by the transformer 40. The temperature of the vapor is here raised to preferably from 1000°F. to 1100°F. by the tap changer 41. A smaller portion of the 100 cracked oil vapor passes down through pipe 45 to coil 47 and is cooled and withdrawn so that continuous samples may be taken to determine the results in the apparatus. The cracked mixture then flows down within 105 condenser tube 50 in a direction counter to that of the water and steam of the surrounding jacket. In this condenser, the mixture is cooled preferably to substantially atmospheric temperature, while the heat transfer medium is reheated. The heat transfer medium will, of course, be heated no higher than the temperature of the oil vapor, and a difference in temperature is necessary to force heat from the steam into the oil of the 110 converter, so that it is necessary to raise the temperature of the steam medium to obtain the desired heat transfer in the converter. This additional heat supply, however, is not lost, since it is absorbed in the oil preheater 120 4 and water preheater 24, where the steam becomes liquid. In case sufficient heat is not carried to the oil preheater and the water preheater in this manner, the furnace or burner 22 operates to supply the difference 125 above referred to.

In the tube 50 the condensed product flows toward the cool end, the tar trap receiving the tar and similar heavy hydrocarbons. The remaining oils and water which are still 130

in gaseous condition continue down the tube, condense, except for the lightest hydrocarbons, and pass into the treated oil tank 66, while the gas which is not condensable at ordinary atmospheric temperature continues to the gas tank 20. The gas in this tank may be utilized in the heaters already described, or may be withdrawn for any desired purpose, if an excess amount is produced.

10 The oil in tank 66 is delivered through pipe 71 to the evaporator and a suitable switch is thrown in on the control board to allow feed of gas to the furnace 72, controlled by valve 74, operated by motor 75, 15 actuated by thermocouple 76, connected with pyrometer, relay and switch on the control board.

10 The automatic equipment is so regulated that the feed to this burner will be controlled 20 so as to hold the temperature of the boiler at the desired distillation temperature. The distilled gases pass up into the pipe 78, and thence down into the condenser tank 77 where the motor spirit is condensed ready 25 for use.

10 In operating the apparatus, the temperature of the continuously moving current of oil vapor and steam is preferably raised with considerable rapidity in the first portion of 30 the converter and more gradually in the latter portion of the converter, its temperature preferably being such that when it enters the cracking or catalyst portion of the tube, it will just be reaching cracking temperature, 35 which is usually somewhere between 800° and 900° F., depending upon the particular oil treated. It will be understood that the current moves continuously through the apparatus with a continuous feed of oil and steam, and that the heat interchanger operates continuously, absorbing heat from the condenser portion of the apparatus and returning it to the preheater and converter portions of the tube. The velocity which 40 we have employed is over seven feet per second, and we have found that this prevents deposits of carbon in the tube. In any event, the current should be maintained at such velocity that any freed carbon is swept 45 along and carried out; and we consider ourselves the first to discover this feature of the operation, namely, that with sufficient velocity of steam flow, the free carbon will be removed and prevented from depositing, where 50 the oil is dropped into the steam. This oil is thus prevented from creeping along the tube and depositing thereon carbon which might not be picked up by the steam if the oil were let in prior to the steam entrance.

10 In Figure 2, we show diagrammatically a form of apparatus similar to that of Figure 1, except that automatic control systems are dispensed with. In this figure, parts similar to those of Figure 1 are designated by similar reference numerals with the letter "a"

applied thereto, the distilling system and the electric control system not being shown. In this case, the apparatus may be regulated by hand control, thermostats and pressure gages being used, if desired, at points similar to 70 those of Figure 1, to give the indications for the control of the several burners, etc. The heat interchanger is retained in this form, the same as in the form of Figure 1, and the lagging or heat-insulating covering is 75 omitted for the sake of clearness.

10 In Figure 3 we show diagrammatically a form similar to that of Figure 2, except that the steam heater is applied to only a part of the converter. In this case, there 80 are three electric leads 100, to the cracking tube and to the latter part of the converter tube, these being connected to a suitable transformer system, utilizing the tubes as heaters to successively step up the temperature. In this case, no differential temperature starting heaters are shown, and in fact, there is no external source of heat shown for supplying heat to the heat transfer system. Parts similar to those of Figure 1 are 85 designated by similar numerals with the letter "b" affixed thereto. Hand regulation or automatic regulation may be used, as 90 desired.

10 In Figure 4, we show a form similar to 95 that of Figure 2, except that no electric heating is supplied, a steam jacket being employed around the catalyst or cracking portion of the conduit, as well as around the converter and oil preheater. In this case, 100 a partition 101 is preferably employed between the catalyst portion of the conduit and the converter portion, and the steam from the differential temperature and starting heater 52° is carried through tube 102 to the jacket 103 around the catalyst portion of the tube and thence through tube 104 to the heater 31°, similar to that of Figure 2. A portion of the steam from this jacket 103 is preferably led through tube 105 direct to the jacket portion 29, 105 encasing the first portion of the converter tube.

10 The other parts of the apparatus are generally similar to those of Figure 2, and are 110 designated by similar numerals with the letter "c" applied. In this case, the heater 53° should be operated in such a manner as to raise the temperature of the catalyst portion of the tube to the desired cracking temperature, usually from 1000° to 1100° F., supplemental heat being continuously supplied to the heat interchange system for 115 this purpose.

10 The advantages of our invention will be 120 obvious to those skilled in the art, since a simple and effective continuous cracking method is provided by which high percentages of cracked product may be obtained. The cracking zones are under close regula- 125 130

tion which we have found very important in obtaining high yields. If electric heat is used, the amount of this heat supplied is greatly reduced by the heat interchange system, if this is employed, thus greatly reducing the amount of external heat supplied to the system. If automatic regulation is employed, this greatly reduces the labor of operation, and insures higher yields when properly adjusted. The dropping of the oil into steam is found to practically eliminate carbon deposit, and thus enable continuous operation to be carried on. The utilizing of portions of the continuous conduit itself as an electric heater or heaters simplifies the system and does away with the need of additional surrounding resisting heat units. It also makes the conduit much more accessible.

As the conduit pipe tends to deteriorate rapidly under the temperatures which we employ, we prefer to provide a conduit of much higher heat resistance than ordinary iron or steel. For this purpose, we propose to use either a calorized steel pipe or a pipe of a special alloy, such, for example, as nichrome. This feature gives longer life to the pipe. The use of a material having a specific electrical resistance higher than iron or steel, such, for example, as nichrome, enables us to use higher voltage and less current to reach the same temperature and also reduces heat losses. The higher voltage permits the use of smaller leads, and therefore affords less opportunity for the conduction of heat from the converter out along the leads.

Pipe of calorized steel, or other material which is less susceptible to the formation of carbon deposits than ordinary steel and iron pipe is preferably employed. Calorized pipe is much less susceptible to the formation of carbon deposits than is the ordinary iron and steel pipe. Apparently, the iron alumina alloy has less affinity for carbon than iron alone. The use of calorized pipe or other pipe having less affinity for carbon than ordinary steel or iron pipe, will permit the reduction of steam velocity or the use of less steam than would be the case in using ordinary steel or iron pipe for the converter tube.

Many changes may be made in the apparatus employed; certain features of our invention may be used without other features; and changes in the steps may be made without departing from the invention involved in our broader claims.

We claim:

1. In a cracking system, a concentric tubular conduit, means for circulating steam through an inner tube, means for dropping hydrocarbon into the steam, electric heating means employing a portion of the conduit as resistance, and a heat interchanger utilizing a heat exchange medium other than hydro-

carbon to withdraw heat from the cracked material and supply it to the heating portion of the system, substantially as described.

2. In a cracking system, a tubular conduit comprising first and second portions and having means for progressively heating the same, said means comprising a heat-interchanging system utilizing a heat exchange medium other than hydrocarbon to withdraw heat from the cracked material, means for further heating said medium, means for supplying said further heated medium to the second portion of said conduit, means for additionally heating said further heated medium after leaving the second portion and supplying the same to the first portion of said conduit.

3. In a cracking apparatus, a continuous tubular conduit comprising a heating portion and a condensing portion, means for continuously feeding oil vapor therethrough, and a heat interchanger arranged to return heat from the condensing portion of the conduit to the heating portion thereof, and means to controllably increase the heat supplied to the heating portion, substantially as described.

4. In a cracking apparatus, a system of double concentric conduits, comprising cracking and condensing portions and a water heating portion, means to pass oil and steam through the inner conduit and therein cracking and later condensing the same, means to conduct cooled fluid from the water heating portion through the outer conduit in the condensing portion, then increasing the temperature of said fluid, and passing it through a section of the cracking portion, and further increasing its temperature and passing it through a different section of the cracking portion and through the water heating portion.

5. In a cracking apparatus, a concentric system of conduits, means to supply oil to the inner of said conduits, means to supply a preheating agent to the outer of said conduits, means to deliver a current of steam under pressure into said inner conduit, automatic means to maintain the preheating agent at predetermined temperatures at different sections of the concentric conduits, a catalyst in said inner conduit, and means to maintain said catalyst at a predetermined temperature.

6. In a cracking apparatus, a concentric system of conduits, means to supply oil to the inner of said conduits, means to supply a preheating agent to the outer of said conduits, means to deliver a current of steam under pressure into said inner conduit, means to supply heated oil to the current of steam, automatic means to maintain the preheating agent at predetermined temperatures at different sections of the concentric conduits, a catalyst, controllable means to in-

dependently heat said catalyzer, and a valved discharge outlet to deliver a controlled portion of the cracked oil from said catalyzer.

- 5 7. In a cracking apparatus, a concentric system of conduits, one of said conduits consisting of anti-corrosive metal, means to supply oil to the inner of said conduits, means to supply a controlled quantity of a 10 preheating agent to the outer of said conduits, means to deliver a current of steam under pressure into said inner conduit, means to supply heated oil to the current of steam, automatic means to maintain the pre- 15 heating agent at predetermined temperatures at different sections of the concentric conduits, a catalyzer, controllable means to independently heat the catalyzer, a valved discharge outlet to deliver a controlled portion 20 of the cracked oil from the catalyzer, a water jacketed condenser leading from said catalyzer, means including a differential heater connecting the water discharge end of the 25 condenser to the outer conduit of the concentric conduits, thermostats located in said inner conduit, electrical governing devices, said thermostats cooperating with said electrical governing devices to control the automatic means and the differential heater.

- 30 8. In the cracking of oils, the steps com-

prising subjecting the oil to increasing predetermined temperatures in contact with a rapid current of steam and under non-carbon depositing conditions, passing said heated oil and steam in contact with a heated catalyzer, recovering the heat from the oil stream after it leaves the catalyzer, controllably increasing said heat, and utilizing said increased heat to preheat said oil and steam. 35

9. In the cracking of oils, the steps comprising subjecting the oil to increasing predetermined temperatures in contact with a rapid current of steam under non-carbon depositing conditions, controlling the temperatures of the oil and steam at different sections of its travel by automatically adding heat to said oil and steam, passing said oil and steam in contact with a catalyzer, maintaining said catalyzer at a high temperature, and conveying the treated oil stream from the catalyzer through a heat exchange condensing system, raising the temperature of the cooling agent of the condenser after it leaves said condenser system and transferring the heat from said cooling agent to the oil and steam stream to preheat the same. 40 45 50

In testimony whereof we have hereunto set our hands.

HANS O. SWOBODA.
EARL M. RICHARDS.
